UNITED STATES PATENT OFFICE.

HIRAM D. TURNER, OF MANCHESTER, NEW HAMPSHIRE.

LAP-STAND.

1,144,161.

Specification of Letters Patent. Patented June 22, 1915.

Application filed May 16, 1914. Serial No. 839,149.

To all whom it may concern:

Be it known that I, HIRAM D. TURNER, a citizen of the United States, residing at Manchester, county of Hillsboro, State of New Hampshire, have invented an Improvement in Lap-Stands, of which the following description, in connection with the accompanying drawing, is a specification, like characters on the drawing representing like parts.

This invention relates to improvements in lap stands for carding machines and is designed with a view to facilitating the introduction of the roll of lap into its supporting guides at the admission end of the carding machine and also to facilitate the piecing of the end of a new lap upon the end delivered from an exhausted roll.

In the usual form of carding machines the rod which forms the axle of the roll of lap is inserted in slots in brackets extending upwardly from the admission end of the carding frame and the lap permitted to rest upon a driven lap roll whereby it is delivered over the feed plate to the feed roll and thence by the licker-in mechanism in the usual manner. The end brackets usually are provided with posts having supplemental brackets having journals adapted to receive the axle of a spare lap which is retained therein until the active roll of lap is exhausted, whereupon the attendants lift the lap from the last mentioned brackets and drop it into active position upon the lap roll.

In order to position the end of the new lap so that it may properly be matted with the end of the preceding lap which is being fed into the carding machine it is frequently necessary to turn the lap which is being introduced forward or backward so that the ends of the laps may be united without forming a ridge or a thin place in the web which is being fed to the carding machine.

One of the objects of the present invention is to provide means for supporting a spare lap in such position that it may be transferred easily into active position without the necessity of touching the material upon the lap thereby avoiding injury to the same.

Another object of the invention is to provide means for rotatably supporting the lap which is being introduced a sufficient distance above its active position to afford access to the edge of the new lap and to per-

mit it to be placed properly relative to the end of the next preceding lap.

Other objects of the invention and the nature thereof will more fully appear from the following description and the accompanying drawings and will be pointed out in the annexed claims.

In the drawings: Figure 1 represents the admission end of the usual carding machine with the improved lap support applied thereto, Fig. 2 is an end view of the same centrally broken away.

As illustrated in the drawing herein the admission end 1 of the usual carding machine frame is provided with a bracket 2 having a vertical slot 3 in which the rod or axle 4 of the active roll of lap 5 is adapted to rotate, the lap being supported upon a lap roll 6 and being delivered therefrom is further advanced by a feed roll 7 to the licker-in and thence to the cylinder.

It is to be understood of course that each side frame of the machine is provided with similar brackets and that the lap stand hereinafter to be described comprises duplicate or complementary parts arranged upon said end frames so both ends of the lap will be simultaneously supported and moved.

The brackets 2 are provided adjacent their upper ends and upon the sides of the slots toward the carding machine with bosses 8 having vertical apertures to receive and support vertical standards 9 upon which means are mounted for supporting a spare lap. The preferred means illustrated herein comprises brackets 10 adjustably mounted upon the standards 9 and secured thereon by set screws 11 or other suitable fastenings. The brackets 10 are provided with laterally extending ears 12 having studs 13 on which are pivoted an angular member one arm 14 of which constitutes a handle while the other arm 15 is provided with means to engage the rods or axle of a roll of lap.

The handle members 14 desirably are connected by a cross bar 16 which may be secured to said members by suitable set screws 17 or other fastenings. The cross bar serves to cause the handles 14 to move in unison and also provides means for supporting the spare lap in elevated position as will herein-after appear.

The ends of the arm 5 are desirably bifurcated, one of the fingers of said bifurcation 18 being curved into hooked form adapted to receive the rod or axle 4 of the

lap while the other finger 19 is extended at an angle to the axis of the portion 5 of said lever to provide a guiding means for directing the axle 4 into the slot 3 in a manner 5 hereinafter to be described.

The axis of the extension 5 is disposed at such an angle to the axis of the handle member 14 that when the latter is in depressed position the axle of the lap which rests in 10 the bifurcation of said lever will be on the same side of the vertical axis of the standard 9 as the rod or stop which connects the levers or handle portions 14 whereby said rod or stop will be pressed against the sides 15 of the standards 9 to support the spare roll in elevated position.

When the material upon the active lap has become exhausted the empty axle is removed from the vertical slot 3 to permit the 20 introduction of the spare lap. The handle 14 is thereupon raised and the spare lap carried about the pivotal support 13 until the member assumes the depending position shown in dotted lines in Fig. 1 at which time 25 the axle of the roll is supported by the hooked finger 18. When in this position the lap is free to be rotated in such a manner that the end thereof may be wound or unwound and easily pieced to the preceding 30 lap.

When the laps have been pieced the handle 14 is thrown still farther over to the left beyond the position shown in Fig. 1, whereby the ends of the axle of the lap will 35 be caused to contact with the side of the standard 9 adjacent to and above the slot 3 forcing said axle out of its engagement with the hooked members 18 and permitting the lap to drop into active position the axle of 40 the roll being guided and steadied in its descent by the inclined finger 19.

It will be observed that the mechanism above described provides a convenient means for supporting the spare lap and transferring 45 the same into active position in the carding machine.

It is to be understood that the mechanism described herein is one of the preferred forms of my invention but that this invention 50 contemplates broadly means for supporting a lap or like device in proximity to its active position, and means for moving the same thereover into active position in the machine in which it is to be used.

It is also to be understood that means may 55 be provided for holding the spare lap at any intermediate position upon the stand.

Having thus described my invention what I claim as new and desire to secure by Letters Patent is:

1. In an apparatus of the class described comprising means for supporting a lap in active position, pivotally mounted means for supporting a spare lap conveniently near 65 said active position and adapted upon ro-

tation to position said spare lap in the vertical plane of the active position but removed therefrom whereby the end of the lap may be pieced conveniently to the next preceding lap.

70

2. In an apparatus of the class described comprising means for supporting the lap in active position, pivotally mounted means for supporting a spare lap above said active position and for swinging the same adjacent to but sufficiently removed from said active position to permit the end of the lap thereon to be conveniently pieced to the next preceding lap.

75

3. In an apparatus of the class described comprising means for supporting the lap in active position, adjustable means rotatably mounted above said position for supporting a spare lap above said active position and for swinging the same adjacent to but sufficiently removed from said active position to permit the end of the lap thereon to be conveniently pieced to the next preceding lap.

80

4. In an apparatus of the class described comprising means for supporting the lap in active position, pivotally mounted means for supporting a spare lap above said active position and for swinging the same adjacent to but sufficiently removed from said active position to permit the end of the lap to be 90 conveniently pieced to the next preceding lap and means for transferring said roll to active position.

95

5. In an apparatus of the class described comprising a frame having slots to receive the ends of the axle of a roll of lap and to maintain the same in active position, supporting standards adjacent to said slots, a pair of angular levers pivotally mounted at their elbows on said standards each having at one end a hooked member to engage and support the axle of the lap and at the opposite end a handle, a stop carried thereby adapted to engage the side of the standard whereby the axle of the lap when in raised position will be on the same side of the pivotal support as said stop.

100

6. A lap stand comprising a frame having slots to receive the ends of an axle of a roll of lap, standards supported by said frames, members pivotally mounted upon said stands and having means adapted to engage and support the axle of a roll of lap, handles extending from said members at an angle to the axial plane and means carried by said 115 handles adapted to engage said standards to support said lap in raised position.

110

7. A lap stand comprising a frame having slots to receive the ends of an axle of a roll of lap, supporting standards, members having bifurcated ends pivotally mounted upon said standards, one arm of each of said bifurcated ends being hook shaped to support the axle of a lap roll when in elevated or depending position and means for supporting 120

125

130

said member in elevated or depending positions.

8. A lap stand comprising supporting standards, a pair of angular levers pivotally mounted at their elbows upon said standards and each having hooked ends adapted to engage the axle of a lap roll, means connecting the opposite ends of said levers adapted to engage said standards to maintain said lap roll in elevated position and providing means for rotating said hooked ends simultaneously into depending position.

9. In an apparatus of the class described comprising a frame having slots to receive the ends of an axle of a roll of lap, standards secured to said frame adjacent to said slots, brackets on said standards, levers pivotally mounted upon said brackets in the plane of said slots and having bifurcated

ends consisting of hooked short arms and oblique long arms, handles upon the opposite ends of said levers and means connecting said handles adapted to engage the sides of the standard to maintain the lap roll in elevated position and providing means for rotating said hook shaped ends into depending position and upon further movement for displacing the lap roll from the hook shaped member and by the action of the inclined arm steadyng the same as it is delivered into the slots in the frame.

In testimony whereof, I have signed my name to this specification, in the presence of two subscribing witnesses.

HIRAM D. TURNER.
